CROSSING PROTECTIVE SYSTEM

James Moore Evans, Detroit, Mich., assignor to
Grade Crossing Guard Corp., Memphis, Tenn.,
a corporation of Tennessee

Application October 29, 1936, Serial No. 108,149

18 Claims. (Cl. 39—6)

The present invention relates to crossing protective devices of the barrier type, that is, of the type in which a retractable and projectable barrier is supported in a pit in a roadway or other 5 area to be protected, and may be automatically or otherwise projected to a blocking position and retracted therefrom under predetermined operating conditions.

Objects of the present invention are to provide 10 an improved barrier protective system of the above identified type, so constructed and arranged as to insure proper operation under all conditions, and which may be relatively economically manufactured, assembled, and installed.

15 More specific objects of the present invention are to provide a protective system of the above stated character, embodying a plurality of barrier devices, the projecting movements of which are effected by spring mechanism associated 20 therewith, and the retracting movements of which are provided by positive driving mechanism associated therewith; to provide such a system in which the retracting mechanism embodies crankshaft elements suitably connected to the 25 barrier devices, and effective to control the rate of the projecting movement; and to provide such a system in which the connections between the spring or weight operated projecting elements 30 and the barriers, and the connections between the retracting elements and the barriers are resilient.

Further objects are to provide such a system in which the individual barriers are pivotally connected to the associated casings, the pivotal 35 connections being such as to floatingly restrain the barriers against vertical, longitudinal, and transverse movements within the casing; to provide such a system in which the barriers and casings are provided with cooperating abutments, 40 in conjunction with the floating barrier supports, which act to directly transmit impact forces from each barrier to the casing; to provide such a system in which the floating barrier supports comprise spring elements so disposed relative to 45 the barriers and casings as to resiliently oppose vertical, transverse, and longitudinal movements of the barriers; to provide such a system in which the just identified spring elements are positioned adjacent the pivotal connections between the 50 barriers and the casings; and to provide such a system embodying in addition to the just identified spring elements, buffer elements supported within the casings, to cooperate with the forward edges of the barriers to resiliently absorb impact 55 forces applied to the barriers.

Further objects of the present invention are to provide a barrier system as above described, including improved means to enable the retracting mechanism to apply a positive lifting force to the barriers under certain circumstances; to 5 provide such a system in which the just stated force is applied through one or more cams associated with the barrier crankshafts and disposed to engage the barriers and positively force the same upwardly; to provide such a system in 10 which the cams are normally spaced from the cooperating parts of the barrier to permit limited floating movements of the latter independently of the cams; to provide such a system in which the cams are automatically retired after a lifting movement thereof is completed; and to provide 15 such a system in which the cam retiring movements, and restoring movements thereof, are controlled in accordance with the movements of the barriers. 20

Further objects are to provide such a system embodying improved means for locking the barriers in projected position; to provide such locking means embodying one or more pivotally mounted arms, responsive to the barrier position, 25 and swingable into and out of locking engagement with the barriers; to provide such a system embodying improved means for selectively limiting the upward movement of the barriers to predeterminedly adjustable height; and to provide 30 such a limiting means embodying stop members carried by the casings and disposed to cooperate with the lifting mechanism to limit the upward barrier motion. 35

Further objects of the present invention are to provide a barrier system of the above stated type in which the connections between the barriers and the retracting mechanism is of a lost motion type, permitting the barriers to be forcibly depressed against the forces of the lifting 40 springs or weights, independently of the positions of the retracting elements; to provide such a system embodying snubber mechanism to limit the speed of a return movement of a barrier, 45 after a depressing movement, to a predetermined value; and to provide such a system in which the snubber mechanism is connected directly between the barriers and the casings, and while effective to limit upward barrier movement, is ineffective 50 to limit depressing movements of the barriers. 55

Further objects of the present invention are to provide a barrier system of the above stated type embodying an improved driving unit, embodying means to retain the barriers in any one 55

of a plurality of positions against the forces of the lifting mechanism individual to the barriers; to provide such a system in which the barriers embody an improved warning light and signal system, controlled in part by the barrier movements and in part by the drive mechanism; and to provide, in a barrier system, an improved method of supporting a barrier structure in a roadway.

With the above and other objects in view, which appear in the following description and in the appended claims, preferred but illustrative embodiments of the present invention are shown in the accompanying drawings, throughout the several views of which corresponding reference characters are used to designate corresponding parts, and in which:

GENERAL DESCRIPTION

Figures 1, 2, 3 and 3A

Referring first to Figures 1, 2, 3 and 3A, each barrier device comprises generally a barrier 50 which is projectably and retractably supported in a casing 52, supported upon beams 54 extending transversely thereof, and which are suitably imbedded in a pit formed in the roadway with which the device is associated. Preferably, as shown in the diagrammatic view, Figure 3A, each crossing installation includes at least four of the devices, two thereof being mounted at each side of the protected intersection. Each of the illustrated traffic lanes A and B (Figure 3A) is thus provided with two of the devices, one thereof being at the entering side of the intersection and the other thereof being at the departing side of the intersection. In certain instances, it is found practicable to protect only the entering side. Generally, however, it is found advisable to protect each lane, at both the entering and departing sides, in order to prevent an oncoming vehicle from avoiding the barrier by swerving out of the regular lane of travel. All barriers at each side of an intersection are connected together for common control by a single drive unit 55 individual to such side.

In Figure 3A also, it is assumed that each device is sufficiently wide to protect its entire associated lane. To accommodate the devices to lanes of greater width, it will be appreciated that the lengths of the individual devices may be increased. Alternatively, the devices may be made in a variety of different lengths, and two or more thereof connected in end to end relation to accommodate roadways of too great a width to be handled conveniently by a single device per lane. A feature of the present construction is the ready adaptability of the barriers for such end to end duplication, and the adaptability thereof for connection at either end to the driving unit.

As an aid in appreciating the following detailed descriptive matter, the operation as a whole of the device may be briefly summarized as follows:

The approach of a train or other vehicle to the crossing with which the devices are associated, and the approach of which is designed to actuate the device, completes the circuit for the driving motor 57 associated with the drive unit at each side of the intersection. Each motor, accordingly, releases a brake associated therewith and starts, thereby rotating the crankshaft 59 connected thereto, which crankshaft is connected to the barriers 50 through a plurality of connecting arms 61. This action permits a plurality of torsion springs 63 associated with each barrier, to force the latter upwardly, during which movement it rotates about the pivotal connection between the rear corner thereof and the casing. After a short initial raising movement, sufficient to bring the warning indicia on the face of the barrier into view, a controller 65 individual to each drive unit interrupts the motor circuit and applies the brake thereof, bringing the barriers to rest in an initial or warning position. After a suitable predetermined interval, determined by timing mechanism hereinafter described, each controller 65 again places the associated motor 57 in operation, continuing the upward movements of the barriers. At the upper limit position, each motor 57 is automatically stopped by the associated controller 65. Upon reaching the limit positions also, the barriers associated with on-coming lanes are automatically locked in the raised position. The barriers associated with out-

going lanes are preferably not locked, so that they may be depressed to permit movement of vehicles thereover. Preferably, also, the outgoing barriers are lifted to only an intermediate height, limit stops being provided for this purpose.

As the actuating vehicle leaves the intersection, motor 57 is again started in the original direction and, through the arms 61, pulls each connected barrier downwardly in a single, continuous movement, to its original position, against the force of the torsion springs 63. Upon reaching the original position, each motor 57 is again brought to rest by the action of the associated controller 65.

Each barrier may thus be broadly characterized as one which is raised through the influence of the torsion springs associated therewith and which is lowered through the force directly applied thereto through the driving unit. The connection between the driving unit and each barrier is a lost motion one, so that the barrier may be depressed against the force of the torsion spring during the raising rotation of the drive unit, at any time between the initial movement thereof and the time that the limit position locking mechanism is rendered effective. Snubbers 69 are provided to prevent a too rapid or a too high rise of each barrier following such a depression.

The initial lifting movement of each barrier actuates a limit switch 67 individual to each device, which controls the circuit for usual crossing traffic warning lights. The barrier control systems are also so arranged that the barrier movement is accompanied by the actuation of a plurality of lamp units 66 located in the casing, and which, in conjunction with suitable reflectors, act to illuminate the warning indicia located on the face of each device. These lights remain lighted in continuously flashing relation from the time of initial actuation thereof until the barrier reaches a corresponding point in its downward or return movement.

The drive units per se and the control systems therefor form the subject matter of applicant's co-pending application, Serial No. 109,941, filed November 9, 1936, and the warning light structure for the barriers and the control system therefor form the subject matter of applicant's co-pending application, Serial No. 108,150, filed October 29, 1936, both of which are assigned to the assignee of the present application. In addition certain features of the present construction are disclosed and claimed in the application of William G. Miller, Serial No. 125,081, filed February 10, 1937, and of Sulo M. Nampa, Serial No. 113,410, filed November 30, 1936, both of which are assigned to the assignee of the present application.

60 BARRIER AND CASING CONSTRUCTION

Figures 1, 2, 3 and 4

Each barrier 50 is preferably formed as a single, elongated, shell-like casting, generally triangular in shape in vertical transverse section, the back of which is enclosed to form a part of the roadway when the barrier is in depressed position, and the generally arcuate front of which is enclosed to form an impact portion and a protective skirt portion. The ends are also preferably enclosed to constitute protective skirts. The under side is preferably open to accommodate the operating elements associated with the barrier. Each enclosing end skirt 56 of each barrier 50 lies closely adjacent the associated end 58 of the casing 52,

and so acts to prevent dirt and other foreign matter from falling into the casing when the barrier is in the raised position. The forward skirt portion 60 lies closely adjacent the forward, upper edge lip 62 of the casing when the barrier is 5 in raised position and performs a corresponding function. The rectangular dimensions of each barrier 50 and casing 52 are such that in the retracted position, only very small spaces are left around the barrier edges, thus minimizing the 10 entrance of dirt and other foreign matter into the casing.

As described in more detail in the above application, Serial No. 109,941, the forward face of each barrier is provided with suitable warning 15 indicia, such as the letters RR and the word "Stop" preferably outlined in reflecting buttons. Cut-outs are also provided to receive large lenses 64. The lenses are preferably supplied from light sources individual thereto and illustrated as comprising a pair of lamps 66 disposed at either end 20 of the casing adjacent the base thereof. Light from the lamp units 66 is reflected through lenses 64 from a pair of moving reflectors which are moved in accordance with the movements of 25 the barrier. Thus, a substantially uniform angle of incidence is maintained between the roadway and the light transmitted through the lenses. Preferably, the arrangement is such that the light transmitted from the barrier is confined 30 within a relatively narrow band. Accordingly, as the barrier moves upward as hereinafter described, a driver of an on-coming vehicle is confronted with a substantially continuous band of red or other colored light, extending entirely 35 across the roadway and providing a highly effective warning.

The impact portion 68 of each barrier is preferably reversely formed, to present an arcuate engaging surface. The arcuate curvature is preferably such that a substantial area is engaged by a tire of a vehicle which engages the barrier. The inclination of the engaging portion 68 in its relation to the height of the barrier, is determined in accordance with the disclosure of the co-pending application of Edward S. Evans, Serial 40 No. 33,037, filed July 25, 1935, and assigned to the assignee of the present application. As disclosed and claimed in this co-pending application, by properly relating the height and inclination 45 of the engaging face of the barrier, a construction results which, when engaged by a vehicle, forces the front end of the vehicle upwardly with a force sufficient to substantially counteract the forward thrust which would otherwise be given an occupant of the vehicle. Vehicles may thus be stopped by the barriers without injury to occupants of the vehicles.

Each casing 52, one of which, as previously stated, is individual to each barrier 50, is preferably formed of an elongated rectangular box-like casting, open at the top and at the bottom and disposed to be supported in the roadway pit upon the previously identified, transversely extending, I-beams 54. A plurality of transverse, 65 inverted, channel shaped ribs 70 extend between the forward and rear walls 72 and 74 of each casing, and, in cooperation with the hereinafter more fully described buffers 76 carried thereby, act to support the lower edge of the arcuate front face 70 of the associated barrier when the latter is in the retracted position. The lips 62 and 78, associated with the forward and rear upper edges of each casing 52, cooperate with the supporting masonry 80 in maintaining the upper surface of 75

each casing 52 in a flush relation to the roadway. Each device, including a barrier 50 and a supporting casing 52, is preferably shipped to the point of installation in a completely assembled condition. A preferred method of erecting the thus previously assembled device consists in providing the pits in the roadway with a masonry footing 82, which forms a substantial and firm support for the I-beams 54, which carry the casing 52. After thus being preliminarily positioned, the masonry 83 may be poured around each casing 52 at the front and rear sides thereof. In certain instances, it is desirable to form the pit deep enough to provide a chamber 81 beneath the barrier, to afford access for inspection or repair. In certain other instances, as described herein-after in more detail, it is desirable to arrange the barriers for access from above.

SUPPORTING RELATION BETWEEN BARRIER AND CASING
20

Figures 1, 2, 4, 5, 6, 7, and 8

It will be appreciated that, in operation, crossing barriers of the type in question are subjected to an extremely heavy duty. They are required 25 to successfully withstand the impact forces of vehicles of widely varying weights and traveling at widely varying speeds, and are required to bring said vehicles to rest without permitting the passage thereof into the protected intersection. 30 Each barrier and casing is accordingly subjected to tremendous impact forces.

The forces involved in the successful operation of a protective device of the kind in question have shown it to be inadvisable to utilize a usual 35 hinging relation between each barrier and its supporting casing. The present invention provides a hinging relation between each barrier and its supporting case which is such that all impact forces applied to a barrier are transmitted 40 directly from the barrier to the supporting walls or ribs of the casing, and are not transmitted through the elements which form the pivotal connection between the casing and the barrier.

Referring particularly to Figures 4, 6, 7 and 8, 45 the rear edge of each barrier 50 is provided along its length with a plurality of spaced bearing bosses 90, provided with suitable bushings 92, and through which pins 94 are passed. Each pin 94, which may and preferably is provided with a suitable lubricant fitting 96, is journaled in spaced 50 bosses 90 formed at the upper ends of the legs of a spring arm 100. Each spring arm 100 is pivotally connected at its lower end to a boss 102 formed in an associated one of the previously 55 mentioned transverse ribs 70, by means of a pin 104, which passes through the boss 102, and the opposite ends of which are freely received in somewhat elongated slots 106 formed in the lower 60 ends of the legs of the spring arm 100. A compression coil spring 108 is seated between each boss 102 and a pin 110, which depends from a cross-web 112 formed in each arm 100. Each spring 65 108 thus acts to urge its associated arm upwardly so that the lower ends of the arm slots 106 bear against the under side of the associated pin 104. The slots 106, however, permit each arm 100 to be depressed somewhat against the force of the compression springs 108. The arms 100 thus act to floatingly vertically support the rear edge of the barrier 50.

A pair of compression springs 113, associated 70 with each arm 100, act between the back 114 thereof, and the rear casing wall, and serve to continually urge the associated arm 100 in a counter-clockwise direction, as viewed in Figure 4.

One end of each spring 113 bears directly against the base of an associated recess 116 formed in the rear casing wall, and the other end thereof is received in a cup-like member 118, which may be suitably secured to the back 114 of the associated arm 100. 5

Springs 113 are opposed by a single compression spring 120, one end of which bears against the inner face of the back 114 of the associated arm 100, and the outer end of which is fitted 10 over a retaining member 122, which is supported adjacent the web 124 of the U-shaped bracket 126, which is either integrally formed with casing 52 or is suitably secured thereto, with the web 124 thereof spaced inwardly from the rear 15 wall of the casing, and the legs 128 thereof spaced apart sufficiently to receive the associated arm 100. The position, and hence the initial compression of spring 120 is adjustable by means of an adjusting screw 130, which may be locked in 20 position by a set screw 132. Adjusting screw 130 is preferably adjusted so that in a free condition the barrier 50 is held by springs 120 and the opposing springs 113 in a position such that the rear edge thereof is slightly inwardly spaced 25 from the rear wall of the casing, and the forward face thereof is spaced slightly inwardly from the forward wall of the casing.

Two additional springs 134 and 136, which act in opposing relation to each other, are provided 30 to resiliently balance or secure the barrier 50 in a predetermined longitudinal position. Bolts 135 and 137, threaded into the sides of arm 100, pass freely through the legs 128, and are provided with retainers 133 and 131 which seat the outer ends 35 of springs 134 and 136. The other ends of springs 134 and 136 are seated in recesses provided in the legs 128 of the previously mentioned U-shaped bracket member 126.

With the above described arrangement, it will 40 be evident that each barrier 50, supported at a plurality of points along its length, floats vertically of the casing under the restraining influence of the springs 108, floats transversely of the associated casing under the restraining influence of 45 the opposed springs 113 and 120; and floats longitudinally of the casing under the restraining influence of the opposed springs 134 and 136.

In order that forces striking the barrier of sufficient magnitude to overcome the restraining 50 forces of the previously described balancing springs and thus of sufficient magnitude to displace the barrier in the casing, may be transmitted directly between the barrier and the casing, independently of the hinge pins 94 and 104, abutment means are provided to absorb the vertical, 55 transverse and longitudinal components of such forces.

To absorb vertically directed forces, a foot 140 is formed within the barrier 50 adjacent each 60 boss 90 and which, in the free position of the barrier, occupies a position in slightly spaced relation to the upper surface 142 of the associated U-shaped brackets 126. The spacing between 65 foot 140 and the surface 142 is less than the lost motion in the connection between each arm 100 and the associated pins 104. Accordingly, any vertical force of sufficient magnitude to substantially compress the springs 108, causes the feet 70 140 to engage the supporting surfaces 142, so that all of the vertical load transmitted between the rear edge of the barrier and the casing is thus transmitted directly between the feet 140 and the supporting surfaces 142. Vertical forces directed 75

against the front edge of the barrier are absorbed by the hereinafter described buffers 16.

Similarly, to absorb any force sufficient to cause the barrier feet to move rearwardly in the 5 casing, or to the right, as viewed in Figure 4, the previously mentioned rear edge rib formation 78 of the casing 52 is made sufficiently heavy to form a positive support for the rear edge of the barrier when engaged thereby. Rearwardly directed 10 forces, acting on the barrier, are thus transmitted between the barrier and the casing through the engagement of the rear edge of the barrier with the rear upper lip formation of the casing. To similarly transmit directly to the housing forwardly directed forces, that is, forces tending to 15 cause the barrier to move forwardly within the housing or to the left, as viewed in Figure 4, a plurality of arcuately formed ribs 144 are provided in spaced relation along the forward wall 20 of the casing, and which extend toward the rear wall. In the free position of the barrier, the arcuate forward face 60 thereof lies in slightly spaced relation to the ribs 144. A forward movement of the barrier, against the resistance of the 25 springs 120, however, brings the forward barrier face 60 directly into engagement with the ribs 144, which constitute a positive limit to such forward motion, and relieves the springs 120 of further load.

30 Forces acting longitudinally of the barrier, if sufficient to compress one or the other of the springs 134 and 136, bring the ends 56 of the barrier directly into abutting relation to the ends 58 of the casing, which members thus act to directly 35 transmit such longitudinal forces from the barrier to the casing.

Each of the buffer plates 76, one of which is associated with each of the previously mentioned transverse ribs 70, comprises generally a flat upper plate-like portion which forms a seat, and a 40 cylindrical boss portion 150 formed integrally with the seat portion and extending downwardly therefrom. An elongated opening 152 extends through the boss portion and forms a lost motion 45 connection with a retaining pin 154 which passes therethrough, and the opposite ends of which are supported in openings (not shown) in the opposite sides of the channel shaped transverse rib 70. Each pin 154, therefore, acts to loosely prevent 50 displacement of the associated buffer plate 76 from their supporting ribs. The supporting ribs are each provided with recesses or depressions 156 within which the plate portions of the buffers are somewhat loosely received.

55 The under side of each boss portion 150 rests upon an upper spring retainer 157, preferably of circular construction, and the upper surface of the marginal edge of which bears against a seat 158 provided therefor in the associated rib 70. A compression spring 160 is seated between each 60 of the upper retaining member 157 and a similarly constructed lower spring retaining member 162, which is supported upon a seat 164 provided therefor in the base of the associated transverse rib 70.

65 The barrier 50 is provided with an inturned flange 166, which extends throughout the length thereof, and is reinforced at a plurality of spaced points by ribs 168 and by additional ribs 169. In the retracted position of the barrier, the flange 70 70 166 rests upon and is supported by the plurality of buffer plates 76, which floatingly retain the barrier in the position of the parts illustrated in Figure 4 under the influence of the supporting 75 springs 160. Any vertical force acting on the

front edge of the barrier, however, and forcing the latter downwardly, initially compresses the springs 160. If the force is of sufficient magnitude, it compresses the springs 160 sufficiently to bring the under sides of the plate portions of the 5 buffers 76 into engagement with the bases of the recesses 156 provided therefor in the transverse ribs, which recesses thus form a positive limit to such downward movement and act to transmit such vertical force directly from the barrier to 10 the casing through the ribs 70.

A structural feature of importance in connection with the buffer plates and associated spring mechanism is shown in Figure 5. In Figure 5, which shows the upper and lower spring retainers 157 and 162 in section, the lower spring retainer 162 is provided with a drilled opening 170, large enough to freely pass an adjusting stud 172, the threaded end of which is threadably received in an internally threaded opening 174 20 provided in the upper spring retainer 157. The base 176 of the transverse rib 70 is provided with an opening 178 sufficiently large to freely pass the head of the adjusting stud 172. In assembling the parts, the buffer plate 76 is first freely 25 dropped into the recess 156 provided therefor in the transverse rib. Thereafter, the pin 154 is inserted in place. As a preliminary to inserting the spring 160, the adjusting stud is turned into the opening 174 sufficiently far to compress the 30 spring 160 and bring the two spring retainers 157 and 162 sufficiently close to each other that the assembly comprising the spring and the two retainers may be freely slipped between the base of the buffer plate and the upper surface of the 35 portion 176. The final assembly step may consist in withdrawing the adjusting stud 172 sufficiently far to permit the spring 160 to expand and force the lower retainers against the portion 176 and force the upper retainers in the seat 158. 40

RETRACTING MECHANISM, INCLUDING CRANKSHAFT AND CONNECTING ARMS, ICE BREAKERS AND LOCKING ARMS

Figures 1, 2, 9, 10, 11 and 12

45 As previously stated, in a general way, each barrier 50 is provided with a crankshaft 59 which extends longitudinally therethrough, and has a lost motion connection with each of a plurality of arms 61, which are respectively pivotally connected to the upper surface of the barrier. The crankshafts are actuated by the drive units 55 and one complete revolution of each thereof is effective to permit one complete raising movement under the influence of the previously mentioned torsion springs 63 and a complete retracting movement, approximately 180 degrees of travel being involved in each of the projecting and retracting movements. The lost motion connection between each crankshaft and its associated connecting arm permits the barrier to be retracted against the force of the torsion springs, independently of the crankshaft movement. It also permits the barrier movement to be interrupted at any point in its travel, independently 55 of the crankshaft movement, so that the upper limit of travel of a barrier may be determined independently of the throw of the associated crankshaft. During travel of the crankshaft in the lowering 180 degrees of movement, however, the 60 offsets positively engage the connecting arms and correspondingly positively effect a barrier retraction movement.

65 As shown generally in Figures 1 and 2, and in greater detail in Figures 9 and 11, the crankshaft 70 75

59 associated with each barrier 50 is rotatably journaled within the associated casing in bearings formed by pillow blocks 180, which are supported upon the transverse ribs 70 and which may be 5 secured thereto in any suitable manner. As best shown in Figure 11, each shaft 59 is formed in sections 59a and 59b, connected together by members 182 which constitute offsets, and which are keyed by keys 181 to the shaft sections. The 10 number of offsets depends of course upon the number of arms 61 desired. In the illustrated arrangement, two connecting arms 61 are provided. The lefthand end of crankshaft 59, as viewed in Figure 1, extends slightly outwardly to 15 the end of the casing 52, which end is provided with a suitable opening to accommodate the crankshaft, and is coupled to the shaft of the drive unit 55 by a conventional flexible coupling 186. The other end of the crankshaft may be 20 adapted for corresponding connection to the crankshaft of an immediately adjacent barrier.

Referring particularly to Figures 9 and 11, each arm 61 comprises a generally U-shaped member, the free ends of the legs 188 and 190 of 25 which are connected together by a stud 192, and are maintained in substantially parallel spaced relation by a combined spacing and bearing block 194, the curvature of the inner face of which corresponds to the curvature of the shaft portion 30 196 associated with the offset 182 in the crankshaft 59. The two legs 188 and 190 thus define a slot within which the shaft portion 196 may 35 freely move relative to the arms 61 in a direction longitudinally of the latter.

35 The base of each U-shaped arm 61 is somewhat wider than the width of the slot provided for the shaft section 196, and this enlarged portion receives a compression spring 198, one end of which 40 is seated against the base of the U-shaped member and the other end of which bears against a retaining plate 200. Plate 200 is threadably secured to the free end of a stud 202, which freely passes through an opening provided therefor in the base of the U-shaped member, and is provided with a head 204. Each head 204 is pivotally connected by a pin 206 to a clevis 208 either formed integrally with or suitably rigidly secured to the under side of the barrier 50.

45 The parts are shown in Figures 9 and 11 in the projected position, in which the offsets 182 of the crankshafts are in their extreme positions of upward barrier movement. As will be evident, rotation of crankshaft 59 in either a clockwise or a counter-clockwise direction from the position 50 shown in Figure 9, is effective to lower the barrier 50 through the connections between arm 61 and the crankshaft 59, the lowering force being transmitted through the compression springs 198. A resilient connection is thus provided between the crankshaft and the barrier. The lowering movement is also opposed by the torsion springs 63 as hereinafter more fully described.

55 As will also be appreciated the crankshaft position corresponding to the barrier retracted position is disposed approximately 180 degrees from the position illustrated in Figure 9. Assuming the barrier to be in the lower position, a crankshaft rotation in either direction from the retracted position is effective to permit a barrier raising movement under the force applied thereto through the torsion springs 63, as hereinafter described. Through the lost motion connection between the crankshaft portion 196 and each 60 arm 61, the crankshaft 59 is effective to limit the

rate of rise of the barrier 50, but is ineffective to cause a rising movement.

As will be further appreciated, the provision of a structure in which a complete raising and lowering cycle involves 360 degrees of crankshaft 5 movement, avoids the necessity of providing reversing mechanism for the driving motor associated with the driving unit, and correspondingly simplifies the control and arrangement thereof.

In instances where the device remains in the 10 retracted position for long periods of time, and under severe weather conditions, it may be expected that more or less ice will accumulate between the barrier and the casing therefor which may oppose the projecting movement of the barrier with a force in excess of the force applied thereto through the torsion springs 63. In the present construction, the arrangement is such that to initially break loose the barrier, the lifting force applied to the barrier through the 15 torsion spring 63 is supplemented by the driving force of the drive unit. Referring particularly to Figures 1, 2, and 10, a pair of cams 210 are 20 suitably keyed by keys 212 to the crankshaft 59 in position for cooperative engagement with 25 seats 214 formed at the bases of the stiffening ribs 169.

30 Each cam 210 is provided with a major peripheral portion *a* of uniform radius, such as to lie in slightly spaced relation to the associated foot 30 214 when the latter is lowered. The portion *b* which represents an angle of between 40° and 50° is of progressively increasing radius. In the fully retracted position of the barrier, each foot 214 lies in spaced relation to portion *a*. After a 35 cam shaft movement of a few degrees, for example, 15° to 20°, each foot 214 is engaged by the periphery of the associated cam at the low end of portion *b*. The parts are shown in Figure 10 with the foot 214 in engagement with the 40 cam portion of maximum radius, which represents the position attained by the parts after between 55° and 70° of crankshaft travel.

45 In normal operation, in which the forces of the torsion springs 63 are sufficient to lift the barrier, the barrier lifting movements carry the seats 214 away from the associated cams. In instances, however, where the torsion spring forces are insufficient to lift the barrier, the seats 214 may 50 remain in engagement with the associated cams 50 during all or part of the 40° to 50° of crankshaft travel, represented by the angular displacement between the limits of cam portion *b*. In such instances, the cams, due to their progressively increasing radius, apply a positive upward 55 force to the feet 214 which, of course, supplement the forces of the torsion springs and positively breaks loose the barrier. It will be appreciated that, when the thus combined forces finally overcome the resistance to motion of the barrier, the 60 barrier will then rise to the normal position corresponding to the then angular position of the crankshaft. It will be appreciated, also, that the total change in radius of the cam 210, as well 65 as the angular displacement between the points 65 of minimum and maximum radius of the portion *b* thereof of increasing radius, depends upon operating conditions and may, in certain instances, be less than the described displacement, and in other instances, may be more than the described 70 displacement.

75 As stated in the foregoing general description of operation of the device, the barriers associated with the on-coming lanes of travel are arranged to be positively locked in the fully raised posi-

tions by locking mechanism which, while ineffective during the initial raising movements of the barrier, is rendered effective as the barrier reaches its maximum height. It is preferred, 5 however, that the barriers associated with the outgoing traffic lanes be arranged so that they may be depressed at any time, so that vehicles trapped between the incoming and outgoing barriers may pass over the outgoing barriers with- 10 out substantial obstruction. In accordance with the present application, the locking mechanism for the on-coming barriers is directly controlled by the cam shaft associated with each barrier.

Referring particularly to Figs. 1, 2, 11 and 12, 15 a pair of arms 220 and 222 are pivotally supported within each casing 51 by pins 224 and 226, which in turn are journaled in clevises 228 and 230, which may be formed integrally with or rigidly secured to the flanges of the transverse 20 ribs 70. Both the arms 220 and 222 and the elements directly associated therewith are the same and a description of one will serve for both.

Referring particularly to Figures 11 and 12, the arm 220 is of bell crank formation, one arm 25 thereof being provided with a roller 232, disposed to continuously engage the periphery of a cam 234 which is keyed by a key 236 to the cam shaft 59. The cam 234 is of uniform radius throughout substantially its periphery, but is 30 provided with a portion 238 of reduced radius which registers with the rollers 232 at the angular position of the cam shaft 59 corresponding to the fully projected position of the barrier.

The bell crank portion of arm 220, which carries the roller 232, is also provided with a seat 240, against which one end of a compression spring 242 bears. The other end of the compression spring 242 is secured over a boss 244 formed on a rearwardly extending projection of the 40 clevis 228. Spring 242 thus continuously urges bell crank 220 in a counter-clockwise direction, as viewed in Figure 12. Except when the barrier is in the fully projected position, the portion of maximum radius of cam 234 engages roller 232 45 and thus retains the end 246 of bell crank 220 in a position to the right of that shown in Figure 12, in which it is inwardly spaced from the face 60 of the barrier 50. As the barrier reaches its fully projected position, however, the seat 248 provided for co-operation with the end 246 of 50 the bell crank passes above such end. At this time also the cam portion 238 of reduced radius registers with the roller 232, permitting the bell crank 220 to be swung in a counter-clockwise 55 direction under the influence of spring 242, to the locking position shown in Figure 12, in which position, it lies directly below the barrier portion 248, and forms a positive block against downward barrier movement.

60 As soon as a barrier retracting movement is begun by the crankshaft 59, roller 232 is engaged by the cam portion of maximum radius, and is thereby forcibly moved to swing the bell crank 220 out of locking engagement with the 65 face of the barrier. The very short interval of cam shaft movement which is thus necessary before the barrier is released by the bell cranks 220 and 222, is readily absorbed by the previously described springs 190 associated with the 70 retracting arms 61.

As described generally above, it is desirable to 75 permit the barriers associated with outgoing lanes of travel to be depressed at any time. Accordingly, it is preferred to omit the just de- scribed locking mechanism from the outgoing

barriers. Moreover, as described hereinafter, it is preferred to provide mechanism to limit the travel of the outgoing barriers to an intermediate height. This limiting mechanism is preferably directly associated with the torsion spring and 5 is described in connection therewith.

TORSION SPRING LIFTING MECHANISM AND TRAVEL LIMITING MECHANISM

Figures 1, 2, 13, 14, 15, 16, 17 and 18

10

Referring particularly to Figures 1, 2 and 13 through 18, two of the torsion springs 63 are shown as connected between the barrier 50 and the casing 52 for forcibly projecting the barrier to the raised position. The construction and 15 arrangement of both of the springs 63 is the same, so that the description of one will serve for both. It will be understood also that, in a broad sense, a greater number or a lesser number 20 of the springs may be utilized.

Considering particularly the lefthand spring 63 of Fig. 15, the righthand end thereof is rotatably supported upon a hub 260 shown as formed integrally with the reduced rearward portion 262 of one of the ribs 70 (Figure 1). The 25 lefthand end of the just mentioned spring 63 is rotatably supported on a hub 264 which forms part of a generally triangularly shaped lifting bracket designated as a whole as 266. The hub 264 is rotatably journaled upon a trunnion 268 30 which is shown as formed integrally with a bracket 270 which is rigidly secured as by the studs 272 to the rear wall 74 of the casing 52. Certain of the studs 272 also support a spring 35 protective apron 273.

The end 276 of spring 63 is connected to the rear wall 74 of casing 52 by a link 278 of adjustable length. One end of the link 278 is provided with the loop 280 which passes over the free end of the spring, and the other end of the link 278 40 is threaded for cooperation with an adjusting nut 282. The adjusting nut 282 is provided with a tubular shank portion 284, of sufficient length to extend all of the way through the opening 286 formed in the base of the casing, and so 45 protects the threads of the stud 272. The head of the nut 282, it will be appreciated, is sufficiently large to have a bearing engagement with the rim of the opening 286.

The back 290 of the triangular lifting bracket 50 50 is of channel formation, and the upper left-hand corner thereof, as viewed in Figure 13, forms a clevis 292, in which a pin 294 is journaled, which pin forms a pivotal connection between the associated lifting arm 296 and the 55 lifting bracket 266. The channel formation of the back 290 also forms a clevis which supports a pin 298, over which the remaining free end 300 of the associated spring 63 is hooked. Preferably, and as illustrated, the just mentioned clevis portion of each lifting bracket 266 is provided with additional cut-outs, such as 302, which may in certain instances be provided with pins to replace the pin 298 and provide a substantial adjustment of the initial torsional stress to which the associated lifting spring is subjected. This adjustment may, as will be appreciated, be refined by suitably adjusting the nut 282 associated with the link 278, which connects the other 60 end of each spring to the housing.

The lefthand flange 304 of the channel shaped back 290, as viewed in Figure 16, is extended to give the bracket its triangular shape and forms the connection between the back portion 290 and 75

the previously mentioned spring carrying hub 264.

Each arm 296, which forms a connection between the lifting bracket 266 and the barrier, is 5 of a link formation and comprises a boss 310 formed integrally at one end thereof for co-operation with the previously mentioned connecting pin 294, and a second boss 312, resiliently connected to the other end of the arm. The 10 boss 312 is connected by a pin 314 to a clevis 316 provided therefor in the barrier 50. The shank 318 of each boss 312 is slidably received in an opening 320 provided therefor in the end of the arm 296. A compression spring 322 surrounds 15 each shank 318, and is seated between an adjustable nut 324 carried by the latter, and the end of the arm 296. The nut 324 is provided with ears 325 which protrude from either side of the arm 296 and prevent turning thereof. The 20 upper end of each arm 296 abuts the lower surface of the connecting boss 312, so that a positive driving connection is provided between each lifting bracket 266 and the barrier 50.

As will be appreciated, each retracting movement of the barrier 50 under the influence of the crankshaft 59 and the associated connecting arms 61, as previously described, forces the lifting arms 296 downwardly, correspondingly rotating the lifting brackets 266 in a counterclockwise direction, as viewed in Figure 13, and winding up the torsional springs 63 to thereby load the springs. On the other hand, rotation of crankshaft 59 throughout the lifting part of its travel relieves the downward force on the barrier, and permits 35 the torsion springs 63 to unwind under the influence of the previously applied stress, forcing the lifting brackets 266 in a clockwise direction, as viewed in Figure 13, and correspondingly forcing the arms 296 and barrier 50 in the upward direction. The resilient connection between the lifting arms 296 and the bosses 312 associated therewith is useful in preventing sudden jars or impacts against the barrier 50 when in a raised position, from being transmitted directly to the 40 lifting brackets 266. This resilient connection, however, is of particular value where it is desired to provide means for positively limiting the rotation of the lifting brackets 266, as where it is desired to limit the lifting movement of the barriers to a point lower than would be permitted by 45 the travel of the crankshaft 59 and connecting arms 61.

In accordance with the present construction, this supplemental upward movement limiting mechanism is applied to the barriers associated with the outgoing lanes of travel, in order to limit the travel thereof to an intermediate height. This limiting mechanism may, however, be applied to the barriers associated with the on-coming 55 lanes of travel, and so adjusted as to permit the barriers to rise to the full height.

Referring particularly to Figure 14, a relatively heavy U-shaped member 330 is associated with each torsional spring 63. The flanges of each member 330 are connected to associated ones of the transverse ribs 70 by studs 332. Preferably also at least one of the flanges associated with each U-shaped bracket is turned over, as indicated at 334, to co-operate with the base of the 60 associated transverse rib 70 and supplement the securing effect of the studs 332. The web 333 of each U-shaped member 330 is disposed for engagement by the portion 304 of the associated lifting bracket 266 when the latter has rotated to 70 the desired degree, and so forms a positive limit

to further movement thereof. It will be evident that the stop members 330 may be adjusted to limit the travel of the associated barrier to any desired degree. Preferably, in association with the outgoing barriers, the member 330 limits the 5 rise thereof to approximately two-thirds the rise of the barriers associated with the on-coming lanes of travel.

After a barrier's rising movement has been stopped by the stop member 330, any impact or 10 external force applied thereto, tending to cause a further upward movement thereof, is absorbed by the resilient connections between the lifting arms 296 and the associated bosses 312 provided by springs 322.

As will be appreciated, the pins 296 associated with arms 61, and the pins 314 associated with arms 296, are readily removable, to thereby disconnect the barrier 50 from the crankshaft 59 and from the torsion spring mechanism, and permit it to be freely rotated to a position to afford ready access to the interior of the structure from above. To afford access to the pins 296 and 314 when the barriers are retracted, a plurality of hand openings 315, closable by removable plates 25 317, are preferably provided at appropriate points in the barrier upper surface (Figure 13).

SNUBBER MECHANISM

Figures 1, 19 and 20

In practice, the projecting movements of the barriers is usually begun when the train or other vehicle, the approach of which may be relied upon to actuate the barriers, is a substantial distance away from the crossing to be protected. This 35 initial movement may be expected to occur at a time when highway vehicles are too close to the barriers to permit a normal stop thereof. To enable such vehicles to pass over the partially raised barriers, the previously described provision 40 for depressing the barriers against the forces of the torsional lifting springs, and independently of the angular positions of the barrier crankshafts, is very desirable if not essential. Similarly, it may occur from time to time that a vehicle 45 will be trapped between the barriers at either side of an intersection or crossing and in such instances, it is desirable that the barrier construction permit such trapped vehicle to depress the barriers and pass thereover without substantial 50 obstruction.

While it is desirable, under the conditions above-mentioned, that vehicles be able to depress the barriers rapidly and without a too great resisting force therefrom, it is equally desirable to retard 55 the return movements to the raised positions of the barriers, after being depressed. In the absence of a retarding mechanism, substantial injury to the under-frame portions of the depressing vehicles may occur.

With the above considerations in mind, it is preferred to provide the barrier of the present construction with snubber or motion checking mechanism, so connected thereto as to permit a free and unimpeded depressing movement, but 60 to limit the return or raising movement of the barriers to a predetermined value. This predetermined rate of return movement preferably is not greatly in excess of the normal rate of rise as provided by the carrier crankshaft in the normal raising motion of the barriers. Preferably, the snubber is connected directly between each barrier and the associated casing, although, in a broad sense, other relationships are practical.

In the broader aspects of the present invention, 75

the snubber mechanism may be constructed in various ways. One suitable construction is described and claimed in the co-pending application of Sulo M. Nampa, Serial No. 113,410, filed November 30, 1936, and assigned to the same assignee as the present application. An alternative construction is shown in Figures 19 and 20 of the present application, and embodies generally a braking member 340, a one-way or over running clutch member 342, and a connecting member 344, by which the snubber is connected to the barrier 50. The just identified elements are supported within the casing 52 upon a forwardly extending bracket 346, secured to the rear casing wall by studs 348, and provided with a plurality of bearing bosses 350, 352, and 354, within which the shaft elements of the snubber are journaled. The connecting element 344 comprises a triple sprocket wheel which is drivingly connected by a pin 341 to the snubber drive shaft 343. A multiple sprocket chain 345 is trained over the sprocket wheel, and one end thereof is connected to the under surface of the barrier 50 by a clevis 347. The other end of the sprocket chain is similarly connected by a clevis 349 to an inwardly turned flange portion 351 provided at the base of the forward face of the barrier 50.

With this arrangement, it will be seen that an upward movement of barrier 50 causes, through the sprocket chain 345 and the sprocket 344, a clockwise rotation of the snubber shaft 343, as viewed in Figure 19, and that a downward or depressing movement of the barrier effects a counter-clockwise rotation of shaft 343, as viewed in the same figure.

The clutch member 342 comprises a pair of opposed housing members 353 and 355, which are suitably secured together to form an enclosed chamber, and which chamber is drivingly connected to the snubber brake shaft 357 by a tapered pin 356, which passes through brake shaft 357 and also through the hub of the left-hand housing member 353, as viewed in Figure 20. The mechanism within the clutch housing (not shown in detail), may comprise, for example, a plurality of dogs drivingly connected to the housing members, and a plurality of ratchet members drivingly connected to the drive shaft 343, which extends into the clutch housing. The relation of the dogs and ratchets is such that counter-clockwise rotation of the drive shaft 343, which corresponds to a depressing movement of the barrier 50, permits the dogs to be cammed out of operative relation to the ratchet teeth but that clockwise rotation of shaft 343, brings the dogs into driving contact with the ratchet teeth. The distribution of the dogs and the ratchet teeth may be such that only a limited angular rotation in the driving direction is necessary to bring the dogs into positive driving relation with the ratchet teeth. Substantially no lost motion in the driving direction is, therefore, present in the operation of the clutch.

The braking element 340 of the snubber comprises a stationary brake member 358, non-rotatably secured to the supporting structure, and through which the brake shaft 357 passes and a movable brake member 359 which is axially movable into and out of braking engagement with member 358, and is drivingly connected, as previously stated, to the clutch member 342 by the pin 356. The movable braking member 359 is relatively heavily formed to give it a flywheel effect, and may be drivingly connected to the

clutch housing 353 through a detent connection comprising a plurality of cams formed thereon which engage in tapered notches formed in the face of the hub of member 353 (not shown). A spring may be seated between the movable and stationary brake members to urge the cams into the notches to render the driving connection effective.

With this arrangement, it will be appreciated that rotation of the drive shaft 343 in a clockwise direction, as viewed in Figure 19, which represents the driving direction of the clutch 342, effects a corresponding rotation in the same direction of the hub 353; and also effects rotation in a corresponding direction of the movable brake member 359 through the detent connection. As long as the rates of rotation of the movable brake member 359 and the hub 353 are the same, it will be appreciated that brake member 359 does not move axially. If, however, a relative rotation occurs between brake member 359 and hub 353, the former is caused to advance or recede relative to the stationary brake member 358, by the riding up of the cams along the walls of the notches.

Due to the flywheel effect of the movable brake member 359, the movable brake member 359 lags behind the hub 353 in response to any acceleration of the latter. This lag causes the movable brake member to move into engagement with the stationary brake member 358, thereby imposing a drag thereon and also imposing a drag on the hub 353. In instances where the shaft 357 tends to accelerate at a relatively high rate, the braking effect thus provided is substantial and may become so great as to bring the brake shaft 357 to rest. As soon as hub 353 assumes a position of rest, the torsion spring is effective to break the brake members 358 and 359 loose from each other by forcing the cam into the notches again, and thus release the hub 353. A rotative advance of the hub 353 may, therefore, occur in a series of starts and stops, the net rate of advance being limited to a suitable desired value, determined by the design characteristics of the snubber elements. The snubber, accordingly, effectively acts to prevent a rise of the barrier 50 in excess of a predetermined value, while at the same time, because of the over running nature of the clutch 342, does not interfere in any way with a depressing movement of the barrier 50.

SUMMARY OF OPERATION AS A WHOLE

Summarizing the operation of the system as a whole, all of the barriers at protective crossings normally occupy the retracted positions in which the upper barrier surfaces lie flush with the supporting roadway and act as continuations thereof, and in which positions they are held by brakes associated with the drive units. In response to the approach of a train or other vehicle to the crossing to be protected, the motor 51 of the drive unit 65, one of which is provided at each side of the crossing, starts in operation, initiating a projecting movement of the barriers connected thereto. The projecting movement occurs due to the force directly applied to the barriers through torsion springs 63 individual thereto, but at a rate determined by the rate of angular movement of the crankshaft 59 of the barriers. In the event that the lifting forces applied to the barriers through the torsion springs are ineffective to cause an upward movement thereof, as in instances where ice has collected within the barriers, the ice breaking cams 210 carried by the

crankshafts supply positive lifting forces to the barriers through the cooperating feet 214 provided on the barrier ribs.

When the barriers reach an intermediate height, which may be called a warning height, the controller 65 associated with each drive unit 55, automatically brings the associated motor 57 to rest, correspondingly stopping the barriers connected thereto. The brake elements associated 10 with each drive motor 57 retain the barriers in positions of rest against the lifting forces of the torsion springs.

At the expiration of a predetermined interval, determined by the timing mechanism associated 15 with the controller 65, each motor 57 is again automatically started and permits the barrier projecting movement to be continued to a limit position under the influence of the torsion springs 63. The barriers associated with the on-coming traffic 20 lanes are permitted to continue to a maximum projected height, in which position they are automatically locked against downward movement by the locking arms 220 and 222. The barriers associated with the outgoing lanes of travel are 25 preferably interrupted at a height intermediate the warning height and the just identified maximum height, this interruption being provided by the stopping members 330, which engage the lifting bracket 266 associated with the torsion 30 springs 63.

The on-coming and outgoing barriers thus occupy the last mentioned projected positions thereof as long as the vehicle which initiated their operation remains within a predetermined block 35 associated with the intersection. As soon as the actuating vehicle passes beyond such block, the motors 57 associated with the barriers at the opposite sides of the intersection are again placed in operation, rotating in the same direction, and 40 act through the arms 61 associated with the crank shafts 59, to forcibly retract the barriers against the forces of the torsion springs 63. When the barriers reach the original retracted positions, the motors 57 are again stopped and the brake 45 elements thereof automatically applied, and so retain the barriers in the retracted position against the forces of the torsion springs 63.

As an incident to the actuation of the barriers, the warning light systems associated therewith 50 are automatically placed in operation in accordance with the disclosure of the previously identified application, Serial No. 108,150, filed October 29, 1936, and serve to provide an effective warning of the barrier action.

55 The lost motion connections between each crankshaft lifting arm 61 and the associated crank 59 permit the outgoing barriers to be forcibly depressed against the forces of the torsion springs 63 at any stage in the movement thereof, and permit the on-coming barriers to be depressed except at such times as the locking arms 220 and 222 are in locking position. The depressing movements of the barriers are unimpeded by the snubber mechanism, but the return movements thereof are maintained at a low rate, commensurate with the normal rate of rise thereof. Vehicles too close to the barriers to permit a 60 normal stop thereof at the time the upward movement thereof is begun, as well as vehicles 65 trapped between the barriers, are permitted to pass thereover without substantial obstruction.

In view of the resilient floating connections 70 between each barrier 50 and the associated casing, provided by the springs 108, 113, 120, and 134 and 75 136, as well as by the buffer plates 76, each barrier

50 is normally supported in slightly spaced relation from the rear, front, and end walls of the associated casing. The just identified springs also resiliently oppose any vertical, transverse, or longitudinal impact forces to which a barrier 5 is subjected. In the event such forces are of sufficient magnitude to overcome the spring resisting forces and cause substantial movements 10 of the barriers within the casings, the barriers are brought into engagement with abutments provided in the associated casings, and such forces are, therefore, transmitted through such abutments directly between the barriers and the casings.

MODIFIED ICE-BREAKING CAM CONSTRUCTION

15

Figures 21 and 22

20

Referring particularly to Figs. 21 and 22, an ice-breaker cam construction is illustrated, which represents an improvement over the construction described particularly with reference to Figs. 10 and 11, for the reasons that, among others, the ice-breaking cams are automatically retired from co-operative relation to the barrier feet after a predetermined amount of crankshaft travel, in order that the barrier feet may not strike the raised portion of the cams when the barriers are forcibly depressed, as by the passage thereover of a vehicle.

25

In Figs. 21 and 22 the general construction and operation is as described with reference to the preceding figures, which relation is indicated by the use of corresponding reference characters with the subscripts *b*. The cams 410, a plurality of which are used, as in the case of cams 210, and all of which are similarly constructed and arranged, are splined as by keys 412 to the crankshaft 59b, for movement between the illustrated position and a retired position to the left thereof. Each cam 410 comprises a portion 415 40 extending between the characters *x* and *y* which is of progressively increasing radius. In the normal or fully retracted position of the parts, each barrier foot 414 lies in slightly spaced relation above the portion 415 of the associated cam 410, 45 permitting a limited amount of free floating action of the barrier, as previously described. In such retracted position the barrier feet 166b rest upon and are supported by the buffers 76b.

50

In addition to being provided with the cam portion 415 of increasing radius, each cam 410 is also provided with a radially extending fin 416, disposed in axially offset relation to such cam portion. In the retracted positions of the parts, each fin 416 lies between the associated foot 414 55 and a downwardly projecting finger 418 secured thereto as by a stud 420.

55

Each cam 410 is also provided with a restoring cam portion 422 which extends through a circumferential angle of about 120°, and which 60 co-operates as hereinafter described with a stationary stop 424 to restore the member 410 to the illustrated position from a retired position to the left of that shown. Each stop 424 is carried upon a bracket 426, suitably and rigidly secured 65 to one flange of one of the transverse ribs 70b. A spring 428, individual to each cam 410, having its opposite ends secured to the shaft 59b, as by the stud 430 and to the cam 410 respectively, is under tension when the parts are in the positions shown, and thus acts to urge the associated cam 410 to a position to the left of that shown in which retired position it is out of range of the associated foot 414.

70

In the normal operation of the parts, a raising 75

- movement of the barrier 50b is initiated by rotating the crank shaft 59b in the counter-clockwise direction as viewed in Fig. 24. As previously described, this rotation of the crankshaft 59b 5 renders the torsion lifting springs effective to project the barrier upwardly. This upward projecting movement of the barrier carries feet 414 away from the associated cam portions 415 at a rate which is in excess of the rate of increase of the cam radii between the points *x* and *y*. It also carries the finger 418 away from the fin 416 at a rate in excess of the rate of increase of the radius of fin 416. Accordingly, a relatively small angular movement of the crankshaft 59b 10 normally permits the barrier 50b to rise sufficiently to bring each finger 418 out of range of the associated fin 416. This slight angular movement of the crankshaft also moves each cam 422 beyond the range of the associated stop 424. These actions release the cams 410, and permit them to move to the left under the influence of the springs 428. This leftward movement moves each cam 410 out of alignment with the associated seat 414. Accordingly, should the barrier 50b be forcibly depressed at any time after the just mentioned slight angular movement of the crankshaft 59b, 15 the cam 410 does not interfere with the depressing movement.
- On the other hand, if the barrier is forcibly retained in the retracted illustrated position, by an accumulation of ice, or the like, the torsion lifting springs may not exert a sufficient force to initiate the barrier projecting movement. In this instance while the slight angular movement 20 of the crankshaft 59b is sufficient to bring the cams 410 out of range of the stops 424, axial movement of the cams 410 to the retired position is prevented both by the friction between the cams 415 and the seats 414 and/or by the engagement between the fins 416 and the fingers 418. Cams 410 thus remain in alignment with the associated seats 414 until such a time as the cam rotation moves the fins 416 out of range of the fingers 418 or, at least until the positive upward lifting force applied to the feet 414 by the cams 415 "breaks loose" the barrier. When the cams 415 "break loose" the barrier, the barrier immediately rises to a position corresponding to the then angular position of the crankshaft, 25 moving fingers 418 away from the fins 416, and permitting the cams 410 to be pulled to the left under the influence of the spring 428. It will be seen, accordingly, that the release of each cam 410 to its retired left-hand position occurs 30 immediately after the breaking loose of the barrier, and occurs immediately after the barrier rises far enough to release the fins 416 from the fingers 418.
- Considering now the downward or retracting movement of the barrier as effected by the crankshaft 59b, continued rotation of crankshaft 59b in the counter-clockwise direction is effective, through arms 61, to pull the barrier downwardly against the force of the lifting torsion springs. 35 In the course of this continued counter-clockwise movement of crankshaft 59b, each cam 422 is brought opposite the associated stop 424. Continued counter-clockwise rotation, accordingly, renders stops 424 effective to force cams 410 to the right as viewed in Fig. 22, against the force of the springs 428. The continued counter-clockwise rotation of the crank shaft 59b also brings the end 416a of each fin 416 into range of the associated finger 418 and foot 414. This occurs 40 at a time when each stop 424 has moved the mem- 45 ber 410 sufficiently far to the right to enable each pin 416 to enter the space between a finger 418 and a foot 414. By the time the crank shaft rotation brings the barrier to the fully retracted position, accordingly, the ice-breaking structure 5 again assumes the position shown in Figs. 21 and 22, in which positions the parts are in readiness for a duplicate operation.
- Although specific embodiments of the present invention have been described, it will be evident 10 that various modifications in the form, number and arrangement of parts may be made within the spirit and scope of the invention.
- What I claim is:
1. In a protective system embodying a casing and a barrier hingedly supported therein for selective projection and retraction, the combination of a hinge arm swingably connected at one end to said barrier and swingably connected at the other end to said casing, and spring means 15 acting on said arm to resiliently oppose vertical, transverse and longitudinal components of impact forces on said barrier.
  2. In a protective system embodying a casing and a barrier pivotally supported in said casing, 20 said barrier having an impact surface disposed when in retracted position to lie in slightly spaced relation to a forward wall of said casing, means for resiliently opposing movement of said impact surface into engagement with said forward wall, 25 and a plurality of ribs disposed along said forward wall for engagement by said impact surface to transmit forces directly between said barrier and said casing.
  3. In a protective system embodying a casing 30 and a barrier pivotally supported therein for selective projection and retraction, said casing having a lower supporting surface for cooperation with a lower edge of said barrier when the latter is in retracted position, the combination 35 of resilient means for resiliently supporting said barrier within said casing including a plurality of buffers distributed along said lower casing surface, each of said buffers being constructed and arranged to resiliently support a forward edge 40 of said barrier and to provide a positive abutment to limit downward movement of said barrier within said casing.
  4. In a protective device, a barrier, means for supporting said barrier for movement between 45 retracted and projected positions, means including one or more springs connected between said barrier and said support for continuously urging and effective to move said barrier to a projected position, and means including a drive shaft connected to said barrier for moving said barrier from a projected position to a retracted position and for retaining said barrier in said retracted position against the force of said springs.
  5. In a protective system, a barrier, means including a casing for supporting said barrier for movement between a retracted and a projected position, continuously acting means including a spring connected between said barrier and said casing for urging said barrier to the projected position, a crankshaft, means connecting crankshaft to said barrier, said crankshaft serving to retract said barrier to the retracted position against the force of said continuously acting means, and means for locking said crankshaft in 55 a position corresponding to the retracted position of said barrier.
  6. In a protective system, a barrier, means for supporting said barrier for movement between a projected and a retracted position, continuously 60 acting means for urging said barrier to the pro-

- jected position, means including a drive shaft connected to said barrier for retracting said barrier against the force of said continuously acting means, a swingable arm disposed for movement into blocking relation to said barrier to lock the same in projected position, a spring for urging said arm into blocking position, and a member actuated by said crankshaft for retiring said arm from blocking position.
- 5 7. In a protective system, a barrier, means for supporting said barrier for movement from a retracted to a projected position, means including a plurality of springs for continuously urging and effective to move said barrier from a retracted 10 to the projected position, means including a drive shaft for effecting the return of said barrier to the retracted position against the force of said continuously acting means, and means acting on said drive shaft to retain it at rest in a predetermined position so as to retain said barrier in a corresponding position.
- 15 8. In a protective system, a selectively projectable and retractable barrier, a casing for supporting said barrier adapted to be imbedded in a roadway; means for pivotally mounting said barrier in said casing, including hinge mechanism disposed to resiliently oppose vertical, longitudinal and transverse components of forces acting on said barrier; means including a plurality of 20 springs having one end connected to said casing, a plurality of resiliently constructed links for connecting the other ends of said springs to said barrier to render said springs effective to continuously urge said barrier to the projected position; 25 a crankshaft; a plurality of resiliently constructed arms forming a lost motion connection between said crankshaft and said barrier for rendering said crankshaft effective to retract said barrier against the force of said springs, and for permitting a retracting movement of said barrier independently of the position of said crankshaft; snubber mechanism acting between said barrier and said casing for limiting a projecting movement of said barrier; and control mechanism for 30 said barrier including means to rotate said drive shaft and to lock said drive shaft in any one of a plurality of rotative positions.
- 35 9. In a protective system, a barrier, means for supporting said barrier for movement between a retracted position and a projected position, means 35 acting between said barrier and said supporting means for urging said barrier to the projected position, additional means disposed to apply an initial abnormal actuating force to said barrier to start the same from said retracted position, and means cooperating with said additional means for moving said additional means to a retired position out of cooperative relation to said barrier.
- 40 10. In a protective system, a barrier, means for supporting said barrier for movement between a retracted position and a projected position, means 40 acting between said barrier and said supporting means for urging said barrier to the projected position, additional means comprising a cam disposed to act against said barrier to apply an additional abnormal actuating force to said barrier, and means for selectively moving said cam to a retired position out of range of said barrier and 45 for restoring said cam to a position in which it is effective to engage said barrier.
- 50 11. In a protective system, a barrier, means for supporting said barrier for movement between a retracted position and a projected position, means 50 acting between said barrier and said supporting
- means for urging said barrier to the projected position, a cam disposed for movement between a retired position and an active position, means carried by said barrier for engagement by said cam when said cam is in the active position, and means controlled in accordance with the position of said barrier for moving said cam between said retired and said active position.
- 55 12. In a protective device, a casing, a barrier movably mounted in said casing for movement between projected and retracted positions, means forming a connection between said barrier and said casing for defining the path of movement of said barrier relative to the casing, and spring means for resiliently holding the barrier in spaced relation to the casing in opposition to impact forces acting on the barrier, said barrier and said casing having cooperating portions disposed to abut each other and directly transmit said forces to said casing upon undue stressing of said 60 spring means.
- 65 13. In a protective device, a casing, a barrier movably mounted in said casing for movement between projected and retracted positions, means forming a connection between said barrier and said casing for defining the path of movement of said barrier relative to said casing, and a plurality of spring elements arranged to resiliently hold said barrier in spaced relation to said casing in opposition to respective vertical, transverse, 65 and longitudinal impact forces on said barrier, said casing and said barrier having cooperating parts disposed to directly abut each other so as to directly transmit said forces to said casing in the event the corresponding springs are unduly stressed.
- 70 14. In a protective device, a casing, a barrier pivotally mounted in said casing for swinging movement between retracted and projected positions, means forming a pivotal connection between said barrier and said casing, and spring means for urging said barrier into a position in which it lies in spaced relation to said casing, in opposition to impact forces on said barrier, said barrier and said casing having cooperating surfaces disposed to be moved into direct abutting relation to directly transmit said forces from said barrier to said casing in the event said spring means is unduly stressed by said forces.
- 75 15. In a protective device, a casing, a barrier, means hingedly supporting said barrier within said casing for movement between projected and retracted positions, including a hinge arm, means forming a pivotal connection between one end of said hinge arm and said barrier, means forming a second pivotal connection between said hinge arm and said casing, and spring means disposed to normally hold said barrier in spaced relation to said casing in opposition to impact forces acting on said barrier, said casing and said barrier having cooperating surfaces disposed to be moved in direct abutting engagement so as to directly transmit said forces to said casing in the event said spring means is unduly stressed by said forces.
- 80 16. In a protective system, a barrier, means for supporting said barrier for movement between a retracted and a projected position, means including a rotatable shaft effective upon rotation to cause said barrier to move to the projected position, a cam carried by said shaft, and a foot formed on said barrier for direct engagement with said cam.
- 85 17. In a protective system, a barrier, means for supporting said barrier for movement between 85

5 a projected and a retracted position, means including a drive shaft for controlling said movement, a link connected between said barrier and said drive shaft, and cushioning means associated with said link for preventing direct transmission of the impact forces on said barrier to said crank-shaft.

18. In a protective system, a barrier, means for supporting said barrier for movement between

a projected and a retracted position, means including a drive shaft for controlling said movement, means including a link for forming a lost motion connection between said shaft and said barrier, and spring means associated with said link for preventing direct transmission of the impact forces on said barrier to said shaft. 5

JAMES MOORE EVANS.
